METHOD AND APPARATUS FOR MAKING RADIOGRAPHIC DIAPHRAGM

Arthur J. Kizaur, Wauwatosa, Wis., assignor to General Electric Company, a corporation of New York

Application June 18, 1951, Serial No. 232,074

14 Claims. (Cl. 18—1)

The present invention relates in general to radiography, that is to say, the art of making X-ray photographs, and has more particular reference to an improved radiographic diaphragm of the sort commonly designated as a "Bucky" diaphragm, and used in radiography to improve picture definition, the invention including improved apparatus and procedures for making the diaphragm.

The function of Bucky type diaphragms and the method of using the same in radiography are well known. Such diaphragms comprise alternate grid strips of lead or other substance opaque to X-rays, and strips of wood or other X-ray transparent material, the strips being arranged to form a composite plate or diaphragm in which the strips extend transversely of the diaphragm and are angulated so as to permit only rays emanating directly from a primary source of X-rays to pass through the diaphragm, while absorbing and thus excluding from the ray sensitive material being exposed all indirect, secondary, reflected or incidental rays originating from other than the primary source.

Radiographic diaphragms of the sort heretofore provided are relatively costly, due to the difficulties of arranging the exceedingly fine gauge metal strips in spaced relationship and accurately angulated in the grid structure; and much effort has heretofore been expended in seeking means for reducing the cost of making diaphragms, while at the same time improving the precision of strip angulation and preserving the individual fine gauge strip material in flat, unbuckled condition in the structure, the U. S. Patent No. 2,115,755, which issued May 3, 1938, on the invention of Julius B. Wantz and Arthur J. Kizaur, describing previous efforts made toward reducing the cost and improving the quality of Bucky type diaphragms.

An important object of the present invention is to simplify and reduce the cost of making Bucky type radiographic screens by providing for the assembly and angulation of fine gauge metal diaphragm strips and the application of X-ray transparent material therebetween, as a continuously progressive procedure accomplished in a direction lengthwise of the strips, to thereby avoid the inaccuracies and time consumption of the laborious, piece-meal assembly operations heretofore considered necessary in producing diaphragms of the character mentioned.

Another important object is to provide for building radiographic diaphragms by first fixing the metal grid strips of the diaphragm in parallel, spaced apart, and relatively angulated position, as in a suitable jig, and then applying X-ray transparent material in situ between the positioned strips; a further object being to maintain the metal grid strips under slight tension to assure that the same remain in flat condition during the application of the X-ray transparent material in situ therebetween.

Another important object is to employ a plastic X-ray transparent material as a grid strip spacing medium in diaphragms of the character mentioned; a further object being to provide for the application of the transparent material in fluid condition between the strips, and thereafter to solidify the material in situ between the grid strips, to thereby support the same in accurately angulated relation in the finished screen.

Another important object is to provide novel strip supporting jig means for holding diaphragm grid strips

2

accurately in parallel, relatively angulated relationship during the application and solidification of the X-ray transparent material therebetween.

Another important object is to provide means for applying plastic material in fluid form between the positioned grid strips and solidifying the material in situ therebetween, progressively in the longitudinal direction of the strips from one end of the grid structure toward the other, a further object being to provide a strip combing member movable longitudinally of the strips during the application of the X-ray transparent material therebetween, to maintain the strips in flat, slightly taut, and accurately oriented and spaced condition as the material is applied and solidified therebetween.

Another important object is to provide screen fabricating apparatus including a pan adapted to receive a predetermined quantity of plastic X-ray transparent material in fluid condition, and into which grid strips, supported in parallel and relatively angulated position, as in a suitable jig, may be immersed so that, by moving a strip tensioning comb longitudinally of the submerged strips in the pan, and by solidifying the fluid material behind the comb, the diaphragm may be produced in final form with the grid strips thereof embedded in the solidified material; a further object being to provide auxiliary apparatus, by means of which the pan and its contents may be moved from a heating zone, in which the transparent material is maintained in fluid condition, progressively into a cooling zone for the progressive solidification of the material in situ around the submerged grid strips in the pan, from one end of the pan toward its other end, including means for moving the strip comb in the pan in the direction of the strips and in advance of the solidifying material.

Another important object is to provide an improved radiographic diaphragm comprising preferably metal strips of X-ray opaque material in parallel and accurately angulated position and embedded in solidified X-ray transparent plastic material; a further object being to provide such a diaphragm as a flat plate having protective panels of preferably metallic X-ray transparent material applied thereto, in position covering the opposite faces of the diaphragm plate; a still further object being to provide an edge binding of suitable, preferably metallic material comprising a frame, in position enclosing the edges of the diaphragm plate and of the protective panels to hold the same together as a unit.

The foregoing and numerous other important objects, advantages, and inherent functions of the invention will become apparent as the same is more fully understood from the following description, which, taken in connection with the accompanying drawings, discloses preferred embodiments of the invention.

Referring to the drawings:

Fig. 1 is a diagrammatic view of radiographic equipment, including a diaphragm embodying the present invention;

Fig. 2 is a perspective view of the improved diaphragm;

Fig. 3 is an enlarged sectional view taken substantially along the line 3—3 in Fig. 2;

Fig. 4 is a sectional view taken longitudinally through equipment for making the diaphragm;

Figs. 5 and 6 are sectional views, respectively taken substantially along the lines 5—5 and 6—6 in Fig. 4;

Fig. 7 is a sectional view showing a modified form of tray illustrated in Figs. 5 and 6;

Fig. 8 is a perspective view showing the equipment illustrated in Fig. 4 in combination with auxiliary operating equipment;

Fig. 9 is a perspective view showing traction apparatus for operating the auxiliary equipment illustrated in Fig. 8; and

Fig. 10 is a schematic wiring diagram for controlling the operation of the traction apparatus.

To illustrate the invention, the drawings show, in Fig. 1, radiographic equipment comprising a suitable X-ray

source, such as an X-ray generating tube 11, having an anode 12 forming a substantially point source of an X-ray beam 13, a table 14 for the support of an object 15 to be radiographically pictured, a diaphragm 16 embodying the present invention, and a sheet or film of light sensitive material 17 disposed behind the diaphragm in position to receive an X-ray induced picture of the object 15.

In making radiographic pictures, the presence of objects such as particles or bodies 18, within the field of the useful X-ray beam 13 and capable of being excited by the beam to form secondary X-ray sources, will, in the absence of the diaphragm 16 cause fogging of the X-ray picture in the layer 17. Such fogging, of course, is the result of the action of secondary X-rays emanating from the source or sources 18, thereby impairing the clarity and definition of the resulting picture. Such fogging of the picture, as the result of excitation of secondary X-ray sources by action of the beam 13, may be eliminated by utilizing the screen 16, which is adapted to screen, from the layer 17, substantially all X-rays except those proceeding in a direction radially of the primary X-ray source 12.

To this end, the screen or diaphragm 16 comprises a plurality of laminations or strips 19 of X-ray opaque material, such as lead, the strips extending transversely of the diaphragm and being disposed in spaced apart relationship. The strips 19 are preferably separated and maintained in spaced relationship by material which is transparent to X-rays. In Bucky diaphragms of the sort heretofore provided the opaque grid strips have commonly been separated and held in desired spaced relationship by means of wooden spacing strips, the X-ray opaque grid strips and transparent spacing material being preferably arranged to form a flat plate, in which each grid strip 19 is relatively angulated with respect to the others and lies in a plane passing substantially through the X-ray source 12 provided at the anode of the tube 11.

It will be seen that, if the screen 16 and the sensitive picturing material 17 are held stationary, during exposure of the material 17 to X-light from the source 12, the sensitive sheet 17 will receive a striped or striated image corresponding to the opaque grid strips 19. Since this striped image, comprising so-called "grid lines," is undesirable in an X-ray picture because of interference with the diagnostic clarity of the pictured image of the object 15, means is commonly provided for relatively shifting the screen 16 with respect to the sensitive layer or film 17 during exposure. Ordinarily, the film 17 is preferably held stationary with respect to the object being pictured and the screen 16 is shifted between the object 15 and the film, such movement being accomplished transversely, preferably at right angles, with respect to the longitudinal orientation of the grid strips 19 in the diaphragm or screen. By so moving the screen through a predetermined displacement at a predetermined, preferably uniform rate of speed, depending upon the exposure interval and the spacing of the grid strips 19 in the screen, the striated image of the grid strips may be eliminated in the resulting picture formed in the sheet or film 17.

The general construction of the so-called "Bucky" diaphragm was proposed by Gustav Bucky in U. S. Letters Patent No. 1,164,987, issued December 21, 1915; and the method of eliminating the striated image of the grid strips, by moving the diaphragm or screen relatively with respect to the sensitive film during the exposure interval, was proposed in 1920 by Dr. Holles E. Potter. The Bucky diaphragm, when used in accordance with the technique developed by Dr. Potter, has been found satisfactory in making X-ray pictures where the exposure interval is in excess of five seconds. Improvements and refinements in the original Bucky diaphragm structure and in radiographic technique, including the improvements disclosed in U. S. Letters Patent No. 2,115,755, issued May 3, 1938, on the invention of Julius B. Wantz and Arthur J. Kizaur, and U. S. Letters Patent No. 2,435,823, issued February 10, 1948, on the invention of Glenn W. Files, now permit the production of satisfactory radiographic negatives, free of grid lines, during fractional second exposure intervals.

Among the difficulties encountered in building satisfactory Bucky type radiographic diaphragms is that which arises from the necessity of maintaining the grid strips 19 accurately in relatively angulated position and in flat

planar condition in the diaphragm. Any deviation of a strip from the position which it is required to occupy for optimum radiographic results will introduce corresponding defects in pictures made by X-ray exposure through the diaphragm. The grid strips have thickness of the order of 0.002 inches, and width of the order of $\frac{1}{16}$ to $\frac{1}{14}$ inch, and they are spaced apart in the diaphragm distances of the order of 0.015 inches, it being desirable to make the strips as wide as possible and as thin as possible in the interests of improved picture definition. Radiographic diaphragms also are currently made in square sizes as large as 18 inches, that is to say, square diaphragms having an area of the order of 300 square inches and up, in which the length of the grid strips is of the order of 18 inches, such size being commonly considered to be the practical limit because of the difficulty of maintaining longer and wider strips in accurately oriented and angulated position in the diaphragm structure, such difficulties being augmented by the exceedingly thin, foil-like character of the strip material.

In view of the foregoing difficulties, it has heretofore been the practice to build up radiographic diaphragms by alternately laminating metal foil with layers of X-ray transparent material, such as wood, to form a laminated stack, then cutting laminated blocks of strip-like character from such stack, squeezing the blocks in order to differentially compress the somewhat resilient wooden material thereof so as approximately to angulate the metal grid strips, and finally assembling a series of the strip-like blocks and securing the same together to form the diaphragm. Such a procedure is not only slow, time consuming, costly and laborious, but the grid strips in the resulting screen are only approximately disposed in the required optimum positions of relative angulation. Furthermore, the necessary squeezing operation, to some extent at least, distorts the grid strips, as by bending or buckling the same, and useful results are attained only by carefully selecting X-ray transparent grid spacing material for its uniform squeezing characteristics in the interests of strip angulation accuracy. In addition, the natural resilience of the squeezed spacing material tends to return the parts to normal unsqueezed condition, thereby tending to displace the grid strips from the desired angulated position in the screen, and also to buckle the screen itself.

The present invention provides for the production of Bucky type radiographic diaphragms in which the grid strips are accurately positioned and angulated, and are maintained in flat, accurately oriented, planar position in the screen. The present invention also provides for the fabrication of diaphragms comprising angulated strips and intervening X-ray transparent spacing material as a single, continuous, and substantially automatic operation, thereby eliminating the several laborious steps heretofore required in producing the diaphragm portion of the screen.

To these ends, means comprising a mounting jig 20 may be provided for holding a plurality of grid strips 19 in properly spaced, angulated position, the jig preferably comprising end bars 21 disposed in parallel, spaced relation, and spacing bars 22 detachably secured to the end bars in position extending therebetween for the purpose of securing the bars in spaced, preferably parallel relationship. The spacing bars 22 are preferably secured in readily detachable fashion to the end bars, as by means of screws 23 or other suitable fastening devices, each bar 22 preferably extending between corresponding ends of the end bars 21 to constitute the structure as a preferably rectangular frame, in which the end bars form the opposite ends of the frame.

As shown, the end bars preferably comprise plates having dependent lower edges, the plates being formed with slots 24 opening at the lower edges of the plates and spaced apart and angulated therein to correspond with the desired grid strip angulation and position in the finished grid structure. Accordingly, the grid strips 19 may be assembled, as by hand operation, on the frame or jig 20 in the same relative position to be occupied by the strips in the grid structure, such assembly merely comprising the application of each strip with its opposite ends extending in corresponding slots 24 of the end members 21, said slots being sized to snugly receive and frictionally engage the ends of the grid strips. If desired, each end member may be relieved, as at 25, to provide a space into which may be bent or folded the extremities of the strips, which extend outwardly

of the end members 21; when the strips are mounted on the frame in the slots 24. The grid strips 19 may thus be mounted in the jig or frame 20 in relatively taut, flat condition.

The equipment also preferably includes a comb element 26, comprising a plate-sized element to fit between the spacing bars 22 of the jig in position to be moved longitudinally along said bars from one end of the jig toward its opposite end. To guide and support the comb during such longitudinal movement, the inner, upper corners 10 of the spacing bars 22 may be relieved to form curved or guiding shoulders 27, and the member 26 may be formed with corresponding bearing surfaces for guiding engagement with said shoulders. The member 26 also may be, and preferably is, formed with projecting fingers or lugs 28, which extend outwardly of the spacing bars 22 on the opposite sides of the jig. The comb member 26 also has portions extending between and depending below the spacing bars 22 of the jig, when mounted thereon; the lower terminal edge of said dependent portions 20 extending substantially in a common plane with the lower edges of the end bars 21 of the jig, when the comb is mounted and supported on the end bars. The dependent portions of the comb are formed with spaced notches or slots 24, angulated therein to correspond with the notches 24 of the end bars, each slot 24 of the comb member lying in a common plane with a corresponding registering pair of slots 24 in the end bars 21, when the comb is mounted on the bars 22 of the jig in position extending therebetween. Accordingly, the strips, 30 in being assembled in the slots 24, may simultaneously be disposed in the corresponding slots 24 of the comb, said slots 24 being sized to snugly yet slidingly receive the grid strips therein.

The screen fabricating equipment may also include a shallow pan 29 of preferably rectangular configuration, and sized to snugly receive therein the jig 20 with comb and grid strips mounted thereon. The pan is also adapted to receive X-ray transparent material in fluid condition. Accordingly, the jig 20, with comb 26 and grid strips 19 assembled thereon, may be deposited in the pan 29 to thereby submerge the dependent portions of the comb member and the end bars 21, as well as the mounted grid strips 19, in the grid spacing material when in fluid condition in the pan.

Thereupon, the comb may be moved slowly on the bars 22 from one end of the jig toward its opposite end, such movement allowing the liquid spacing material to flow from in front of the moving comb, as through openings 30 therein, disposed preferably above the slots 24, to the rearward side of the advancing comb. Such comb movement will place those portions of the grid strips, behind the advancing comb, under slight tension by virtue of the combing action of the comb element upon the grid strips, where the same travel through the slots 24. Means is provided for causing the spacing material to solidify in situ around the grid strips behind the advancing comb, whereby to thus embed the strips in accurately spaced and angulated relationship in the solidified spacing material.

To this end, the comb should be moved at the rate of speed at which solidification of the spacing material is accomplished, to thereby maintain the grid strips under tension and in properly spaced and angulated position as the spacing material becomes solidified therearound. Means also is provided for maintaining the spacing substance in free-flowing liquid condition in front of the advancing comb and in a zone of limited extent immediately behind the comb.

Instead of providing for the flow of liquid spacing material through openings 30 in the comb, or in addition to said openings, the bottom of the pan 29 may be formed with parallel grooves or flutes 30, preferably opposite the open ends of the slots 24, to permit the spacing material to flow past the advancing comb member beneath the lower edge thereof.

Any suitable or preferred X-ray transparent spacing material may, of course, be employed. It has been found that a normally solid composition, comprising refined beeswax, either alone or together with other common waxes, may be employed to advantage as an X-ray transparent strip spacing substance, since such composition may be readily reduced to free-flowing condition by heating the same to temperatures of the order of 200° F. Other substances, including thermosetting materials, that

is to say, materials which are initially of fluid character and which may be solidified by the application of heat thereto, may, of course, be employed. In the interests of manufacturing simplicity, however, it is expedient to employ a normally solid material comprising beeswax and other waxes, which may be easily reduced to liquid state by the application of heat thereto and then returned to solid condition at readily regulated rates by chilling the molten substance.

Any suitable or preferred means may be employed for relatively moving the comb member 26 along the jig mounted grid strips 19, and for maintaining the strip spacing material in liquid condition on one side of the comb element and for solidifying it on the other. The present invention, however, contemplates the provision of apparatus in which the pan 29 and jig 20, with grid strips and comb member mounted thereon, may be relatively movably positioned in order to carry out the foregoing procedures. To this end, Figs. 8, 9 and 10 of the drawings disclose a frame structure 31, comprising a table providing spaced, longitudinally extending rails 32 and spaced mounting brackets 33 disposed medially of the table outwardly of the rails.

Suitable means may be provided on or in the table structure to constitute conditioning zones or stations 34 and 35 on opposite sides of the brackets 33. Such zones may respectively comprise heating and cooling stations, where the X-ray transparent spacing medium is of the sort which exists in solid condition at normal atmospheric temperatures and which may be converted to liquid state when heated substantially above normal temperature. Where the spacing medium, however, is of the sort which exists initially in fluid condition at normal temperatures and becomes solid in response to the application of heat, the zones 34 and 35 respectively may be constituted as cooling and heating zones. In either case, the zone 34 constitutes liquid condition station in which the spacing medium may exist or be maintained in fluid condition, while the zone 35 constitutes a solid condition station in which the spacing medium may be caused to become solid.

In the illustrated embodiment, the table structure is provided with a heater 36 to constitute the zone 34 as a heating station. Any preferred sort of heater may be employed, although an electrically energized hot plate mounted in the table between the rails 32 is preferred. Any suitable or preferred cooling means may be mounted in the table 31 to constitute the zone 35 as a cooling zone. Cooling means in the zone 35 may, of course, be omitted where the strip spacing medium is of the sort which solidifies readily at normal atmospheric temperatures.

It will be obvious, of course, that a heater 36 may be disposed in position to constitute the zone 35 as a heating zone, in dealing with a heat hardening spacing medium, in which case, of course, the zone 34 may constitute a cool zone, either by supplying cooling or refrigerating means in the table structure, or by relying upon the cooling effect of normal atmosphere when such is feasible, and depending upon the nature of the spacing medium being used in building the diaphragm.

A carriage comprising a support frame 37 with track engaging rollers 38 is provided for movement on the rails longitudinally of the table structure, said frame 37 being adapted to snugly receive and support the pan 29 and its contents. When so positioned in the carriage frame 37, the projecting fingers or lugs 28 of the comb may be removably positioned and clamped in the brackets 33, to thereby hold the comb member 26 stationary with respect to the table. When initially positioned in the table structure with the comb disposed at one end of the pan mounted jig, it will be seen that the pan and its contents may extend entirely within the liquid condition zone 34.

Means may be provided for moving the carriage frame 37 longitudinally, as on the tracks 32, in order to advance the same between the brackets 33 from the liquid condition zone 34 progressively into the solid condition zone 35, while the comb 28 is held stationary in the brackets 33 in position intermediate said zones. To this end, suitable traction means 39 may be provided, such traction means preferably comprising spaced shafts 40 mounted on the table structure, as at its opposite ends, such shafts carrying sprocket wheels 41 which, if desired, may extend in wheel slots 42 formed in the table structure. Flexible traction members 43 may be mounted

on the wheels 41 and drivingly connected, as at 44, with the opposite ends of the carriage 37. Accordingly, by driving the shafts 40 in one direction or the other, the carriage frame 37 may be moved from the liquid condition zone 34 into the solid condition zone 35 at a desired rate of speed, and may be returned from the zone 35 to the zone 34. It is desirable to provide for moving the carriage frame 37 at an extremely slow speed from the zone 34 into the zone 35, in order to accommodate the relatively slow rate of solidification of the spacing medium behind the comb member 26. At the conclusion of the projecting movement of the carriage frame into the zone 35, the pan and its contents, with the spacing medium in substantially solid condition, may be immediately removed from the carriage frame and set aside for further solidification of the spacing medium, including any desirable or necessary medium curing procedures.

After removal of the tray and its contents from the carriage frame, it is, of course, desirable to provide for the prompt return of the carriage frame to the zone 34 to receive a succeeding tray and contents for a repetition of the screen fabricating procedure. To this end, the traction means 39 may be driven, as by a preferably electric motor 45, which may conveniently be mounted in the table structure 31, the motor being drivingly connected with the traction mechanism through speed changing transmission means 46 drivingly interconnected between the motor 45 and one of the shafts 40. The transmission means 46 may be normally arranged to drive the shaft at relatively slow speed when the motor 45 is energized to turn in one direction, suitable gear ratio changing means, controlled as by a solenoid 47, being provided to cause the traction mechanism to be driven at relatively high speed by the motor when the same is energized to turn in the reverse direction.

As shown more particularly in Fig. 10 of the drawings, the driving means may be controlled by a four-pole, double throw switch 48 interconnected as shown with a suitable source S-S of electrical power, the contacts of two of the poles of said switch being connected with limit switches 49 and 49'. The contacts and blades of the other two poles of the switch may be arranged as a reversing switch and connected with the motor 45 and with the solenoid 47.

The limit switches 49 and 49' may be mounted in the table structure 31, the same being normally closed switches mounted in position to be opened in response to the arrival of the carriage frame 37 at the limit of its retracting and projecting movement, respectively, in the zones 34 and 35. Accordingly, when the control switch 48 is thrown to its downward position, viewing Fig. 10, the carriage frame 37 being in fully retracted position in the zone 34, the motor 45 will be energized to drive in a direction to move the carriage frame from the zone 34 into the zone 35 at a reduced rate of speed, the switch 49' being then in its normally closed position. When the carriage frame 37 reaches its fully projected position in the zone 35, the switch 49' will open and the motor will stop. After removal of the pan 29 and its contents from the carriage frame, the switch 48 may be thrown to its upward position, viewing Fig. 10, which will cause the motor 45 to operate in a direction to retract the carriage frame to starting position in the zone 34, the switch 49 being then normally closed. Such retracting movement may take place rapidly, since the high speed control solenoid 47 will also be energized during such retractive movement of the carriage frame. When the frame reaches the limit of its retracting movement, the switch 49 will open and thereby stop the driving motor 45.

After removal of the tray 29 and its contents from the carriage frame 37 in the zone 35, the jig 20 and comb 26, together with the embedded grid strips 19 and the solidified spacing material 50, may be removed from the pan 29. Thereafter, the embedded grid strips and spacing material may be removed from the jig 20 and comb 26 by transversely sawing the same inwardly of the end bars and comb member, which at such time is positioned adjacent one of the end bars. Thereafter, the edges of the screen element may be trimmed, and the diaphragm may be finished by applying a preferably metallic frame 51 around its edges, the finished diaphragm 52 being shown in Fig. 2 of the drawings.

If desired, prior to the application of the edge bind-

ing frame 51, a thin facing sheet or panel 53 may be applied in position covering each of the opposing faces of the diaphragm. Such finishing sheets 53 may comprise any suitable material, such as aluminum, plastic material, or fiber board, which is substantially transparent to X-rays, the purpose of the finishing panels being, of course, to strengthen the structure and to afford protection for the grid strips and spacing material enclosed therebetween.

10 It is thought that the invention and its numerous attendant advantages will be fully understood from the foregoing description, and it is obvious that numerous changes may be made in the form, construction and arrangement of the several parts without departing from 15 the spirit or scope of the invention, or sacrificing any of its attendant advantages, the forms herein disclosed being preferred embodiments for the purpose of illustrating the invention.

The invention is hereby claimed as follows:

20 1. The method of making a radiographic diaphragm which consists in mounting and supporting grid strips of X-ray opaque material in spaced and relatively angulated position, submerging the strips in a spacing medium in liquid condition, and then solidifying the medium 25 while simultaneously combing the strips to maintain the same in flat condition and in accurately spaced and angulated position as the medium solidifies.

2. The method of making a radiographic diaphragm which consists in mounting and supporting grid strips 30 of X-ray opaque material in spaced and relatively angulated position, submerging the strips in a spacing medium in liquid condition, and then solidifying the medium progressively in a direction longitudinally of the strips while combing the strips in the same direction and in advance of the solidification of said medium, to thereby embed and secure the strips accurately in spaced and relatively angulated position in the solidified medium.

3. Apparatus for making radiographic diaphragms comprising a frame forming a jig, providing spaced mounting members having spaced apart, angulated slots therein for the removable reception of diaphragm grid strips, and a strip comb movable longitudinally on said frame between said mounting members and formed with correspondingly spaced and angulated combing slots for the accommodation of grid strips mounted in the jig, and means for 45 correspondingly spaced and angulated combing slots for the accommodation of grid strips mounted in the jig.

4. Apparatus for making radiographic diaphragms comprising a frame forming a jig, providing spaced mounting members having spaced apart, angulated slots therein for the removable reception of diaphragm grid strips, a strip comb movable longitudinally on said frame between said mounting members and formed with correspondingly spaced and angulated combing slots for the accommodation of grid strips mounted in the jig, and means for immersing said jig and comb, together with grid strips 50 mounted thereon, in a bath of strip spacing medium in liquid condition.

5. Apparatus for making radiographic diaphragms comprising a frame forming a jig, providing spaced mounting members having spaced apart, angulated slots therein for the removable reception of diaphragm grid strips, a strip comb movable longitudinally on said frame between said mounting members and formed with correspondingly spaced and angulated combing slots for the accommodation of grid strips mounted in the jig, means for immersing said jig and comb, together with grid strips mounted thereon, in a bath of strip spacing medium in liquid condition, and means operable to solidify said medium in situ around the strips.

6. Apparatus for making radiographic diaphragms comprising a frame forming a jig, providing spaced mounting members having spaced apart, angulated slots therein for the removable reception of diaphragm grid strips, a strip comb movable longitudinally on said frame between said mounting members and formed with correspondingly spaced and angulated combing slots for the accommodation of grid strips mounted in the jig, a pan sized for the snug reception of said jig, whereby to immerse strips mounted thereon in a spacing medium in liquid condition in the pan, and means for moving the pan and jig relatively with respect to the comb in the longitudinal direction of the jig mounted strips, whereby to comb the strips longitudinally as the medium becomes solidified in the pan around the strips.

7. Apparatus for making radiographic diaphragms comprising a frame forming a jig, providing spaced mounting

members having spaced apart, angulated slots therein for the removable reception of diaphragm grid strips, a strip comb movable longitudinally on said frame between said mounting members and formed with correspondingly spaced and angulated combing slots for the accommodation of grid strips mounted in the jig, a pan sized for the snug reception of said jig, whereby to immerse strips mounted thereon in a spacing medium in liquid condition in the pan, conditioning mechanism comprising adjacent liquid and solid zones for determining the condition of the medium in the pan, and traction means for moving the pan and jig progressively from said liquid to said solid zone, in the longitudinal direction of jig mounted strips, whereby to progressively solidify the medium in the pan in the longitudinal direction of the strips.

8. Apparatus for making radiographic diaphragms comprising a frame forming a jig, providing spaced mounting members having spaced apart, angulated slots therein for the removable reception of diaphragm grid strips, a strip comb movable longitudinally on said frame between said mounting members and formed with correspondingly spaced and angulated combing slots for the accommodation of grid strips mounted in the jig, a pan sized for the snug reception of said jig, whereby to immerse strips mounted thereon in a spacing medium in liquid condition in the pan, conditioning mechanism comprising adjacent liquid and solid zones for determining the condition of the medium in the pan, and traction means for moving the pan and jig progressively from said liquid to said solid zone, in the longitudinal direction of jig mounted strips, whereby to progressively solidify the medium in the pan in the longitudinal direction of the strips, including means for moving the comb with respect to the pan mounted jig to progress the comb along the jig mounted strips in advance of the solidification of the medium.

9. Apparatus for making radiographic diaphragms comprising a frame forming a jig, providing spaced mounting members having spaced apart, angulated slots therein for the removable reception of diaphragm grid strips, a strip comb movable longitudinally on said frame between said mounting members and formed with correspondingly spaced and angulated combing slots for the accommodation of grid strips mounted in the jig, a pan sized for the snug reception of said jig, whereby to immerse strips mounted thereon in a spacing medium in liquid condition in the pan, conditioning mechanism comprising adjacent liquid and solid zones for determining the condition of the medium in the pan, and traction means for moving the pan and jig progressively from said liquid to said solid zone, in the longitudinal direction of jig mounted strips, whereby to progressively solidify the medium in the pan in the longitudinal direction of the strips, including a heater for heating the pan and its contents in the liquid zone.

10. Apparatus for making radiographic diaphragms comprising a frame forming a jig, providing spaced mounting members having spaced apart, angulated slots therein for the removable reception of diaphragm grid strips, a strip comb movable longitudinally on said frame between said mounting members and formed with correspondingly spaced and angulated combing slots for the accommodation of grid strips mounted in the jig, a pan sized for the snug reception of said jig, whereby to immerse strips mounted thereon in a spacing medium in liquid condition in the pan, conditioning mechanism comprising adjacent liquid and solid zones for determining the condition of the medium in the pan, and traction means for moving the pan and jig progressively from said liquid to said solid zone, in the longitudinal direction of jig mounted strips, whereby to progressively solidify the medium in the pan in the longitudinal direction of the strips, including means for abstracting heat from the pan and its contents in said solid zone.

11. Apparatus for making radiographic diaphragms comprising a frame forming a jig, providing spaced mounting members having spaced apart, angulated slots therein for the removable reception of diaphragm grid strips, a strip comb movable longitudinally on said frame between said mounting members and formed with correspondingly spaced and angulated combing slots for the accommodation of grid strips mounted in the jig, a pan sized for the snug reception of said jig, whereby to immerse strips mounted thereon in a spacing medium in liquid condition in the pan, conditioning mechanism comprising adjacent liquid and solid zones for determining the condition of the medium in the pan, and traction

means for moving the pan and jig progressively from said liquid to said solid zone, in the longitudinal direction of jig mounted strips, whereby to progressively solidify the medium in the pan in the longitudinal direction of the strips, wherein said traction means comprises a pan carriage movable from the liquid zone to the solid zone and vice versa.

12. Apparatus for making radiographic diaphragms comprising a frame forming a jig, providing spaced

10 mounting members having spaced apart, angulated slots therein for the removable reception of diaphragm grid strips, a strip comb movable longitudinally on said frame between said mounting members and formed with correspondingly spaced and angulated combing slots for the

15 accommodation of grid strips mounted in the jig, a pan sized for the snug reception of said jig, whereby to immerse strips mounted thereon in a spacing medium in liquid condition in the pan, conditioning mechanism comprising adjacent liquid and solid zones for determining

20 the condition of the medium in the pan, and traction means for moving the pan and jig progressively from said liquid to said solid zone, in the longitudinal direction of jig mounted strips, whereby to progressively solidify the medium in the pan in the longitudinal direction

25 of the strips, wherein said traction means comprises a pan carriage movable from the liquid zone to the solid zone and vice versa, and driving means operable to travel the carriage at slow speed in one direction and at high speed in the other.

30 13. Apparatus for making radiographic diaphragms comprising a frame forming a jig, providing spaced mounting members having spaced apart, angulated slots therein for the removable reception of diaphragm grid strips, a strip comb movable longitudinally on said frame

35 between said mounting members and formed with correspondingly spaced and angulated combing slots for the accommodation of grid strips mounted in the jig, a pan sized for the snug reception of said jig, whereby to immerse strips mounted thereon in a spacing medium in

40 liquid condition in the pan, conditioning mechanism comprising adjacent liquid and solid zones for determining the condition of the medium in the pan, and traction means for moving the pan and jig progressively from said liquid to said solid zone, in the longitudinal direction

45 of jig mounted strips, whereby to progressively solidify the medium in the pan in the longitudinal direction of the strips, wherein said traction means comprises a pan carriage movable from the liquid zone to the solid zone and vice versa, and driving means comprising an

50 electrical motor, transmission means drivingly connecting the motor with the carriage, and motor control means including limit switches operable to stop carriage movement in each direction.

14. Apparatus for making radiographic diaphragms comprising a frame forming a jig, providing spaced

55 mounting members having spaced apart, angulated slots therein for the removable reception of diaphragm grid strips, a strip comb movable longitudinally on said frame between said mounting members and formed with correspondingly spaced and angulated combing slots for the

60 accommodation of grid strips mounted in the jig, a pan sized for the snug reception of said jig, whereby to immerse strips mounted thereon in a spacing medium in liquid condition in the pan, conditioning mechanism comprising adjacent liquid and solid zones for determining the condition of the medium in the pan, and traction means for

65 moving the pan and jig progressively from said liquid to said solid zone, in the longitudinal direction of jig mounted strips, whereby to progressively solidify the medium in the pan in the longitudinal direction of the strips, wherein said traction means comprises a pan carriage movable

70 from the liquid zone to the solid zone and vice versa, and driving means operable to travel the carriage at slow speed in one direction and at high speed in the other, said

75 driving means comprising an electrical motor, transmission means drivingly connecting the motor with the carriage, motor control means including limit switches operable to stop carriage movement in each direction, and carriage speed changing means operable in accordance with the direction of carriage movement.
